APPARATUS FOR PRINTING CONTINUOUS DESIGNS ON ROLL PAPER AND THE LIKE

William B. Chance, St. Clairsville, Ohio

Application August 24, 1951, Serial No. 243,428

3 Claims. (Cl. 101—212)

1

My invention relates to improvements in apparatus for printing a continuous design of a given length on roll paper and similar material.

The primary object of my invention is to provide a practical apparatus for printing continuously a long design or form, repetitious, or otherwise, on roll paper and which is well adapted for comparatively high speed and equally efficient operation on either thin or heavy gauge roll papers.

Another object is to provide apparatus for printing with an endless belt carrying printing plates for printing a substantially continuous form, together with efficient means for inking the plates and maintaining the belt taut during inking of the plates and the printing operation.

Other and subordinate objects, within the purview of my invention, together with the precise nature of my improvements will be readily understood when the succeeding description and claims are read with reference to the drawings accompanying and forming part of this specification.

In said drawings:

Figure 1 is a view in side elevation of my improved apparatus in the preferred embodiment thereof as viewed from one side of the same;

Figure 2 is a view in front elevation drawn to a larger scale;

Figure 3 is a fragmentary view in side elevation of the apparatus viewed from the other side thereof;

Figure 4 is a fragmentary view in vertical longitudinal section taken on the line 4—4 of Figure 2 and drawn to a larger scale;

Figure 5 is a fragmentary detail view in end elevation drawn to a still larger scale of the upper and lower impression rollers, illustrating the direction of run, or drive, of the belt and the paper between said rollers;

Figure 6 is a view in longitudinal section drawn to a larger scale of one of the inking rollers;

Figure 7 is a fragmentary view drawn to a larger scale of the belt and illustrating one arrangement of the printing plates thereon; and

Figure 8 is a view in edge elevation of the same.

Referring to the drawings by numerals, the apparatus of my invention comprises an elongated frame designated, as a unit, by the numeral 1 and including a base 2, a top 3, and at what constitutes the front end of said frame a raised hollow platform structure 4. The front end of the top 3 overhangs the platform structure 4 and rearwardly of said structure the frame 1 further includes uprights 5 spaced apart

longitudinally of the base 2 to form pairs at opposite sides of said frame 1, a front pair of the uprights 5 being shown in Figure 2. The uprights 5 support upper and lower, longitudinal, side bars 6, 7 at each side of the frame 1 between the base 2 and the top 3, the upper bars being substantially above the platform structure 4 and the side bars 7 well below the top 3 of said structure 4. The particular purpose of the described parts of the frame 1 will presently appear.

Adjacent the front end of the frame 1, a pair of upper and lower impression rollers 10, 11 extend transversely of the platform structure 4 between upright side bearing brackets 12 suitably fixed on said structure 4, the lower impression roller 11 being journaled in said brackets and the upper impression roller 10 being journaled in bearings 12' vertically slidable in said brackets by hand operative set bolts 13 for adjusting upper roller 10 vertically relative to said lower roller 11 for a purpose presently seen. Like gears on one end of said rollers 10, 11 connect the same together for drive of the lower impression roller 11 by the upper one, and will be presently explained.

An endless belt 15 drives the upper impression roller 10 and which, for the purpose of arrangement of a belt of considerable length in compact form within the confines of the frame 1, which is substantially shorter, has its upper run trained over a horizontal upper series of transverse idler rollers 16 suitably journaled in the upper horizontal series of bars 6, said upper run being trained under a similar horizontal, lower series of transverse inking rollers 17 journaled in the lower horizontal bars 7, said belt being trained over a pair of spring tensioned belt tightening rollers 18, 19 at the front and rear and below the series of inking rollers 17. The belt tightening rollers 18, 19 are journaled in arms 20, 21 pivoted, as at 22, 23 for vertical swinging on an upright 5 and the base 2, respectively. As will be seen, the rollers 16 are spaced a substantial distance above the rollers 17 and 18, and 19 and the inking rollers 17 and belt tightening rollers 18, 19 form a series staggered laterally with respect to the series of rollers 17 so that the belt 15 is formed by said rollers into a plurality of vertical, successive, closely spaced loops 24 whereby a very long belt can be arranged in a comparatively short frame 1, as will be clear.

From the foremost roller of the upper series 16, the upper run of the belt 15 is trained forwardly over a larger, transverse idler roller 25

journalized in a hanger bracket 26 suspended from the front end of the top 2 of frame 1. From the idler roller 25, the belt 15 extends downwardly around the upper impression roller 10 in front thereof from which it travels rearwardly between said rollers 10, 11.

From the impression rollers 10, 11 the lower run of the belt 15 travels over a transverse idler roller 28 journalized in the platform structure 4 and from which said belt is looped downwardly under a transverse comparatively large driving roller 29 also journalized in said structure 4. Immediately behind driving roller 29, the belt 15 is looped upwardly over a transverse belt tightening roller 30 journalized in bearings 31 on top of said structure 4 and adjustable longitudinally of said structure to adjust said roller 30 for tightening purposes. From tightening roller 30 the belt 15 extends downwardly and rearwardly under a lower transverse idler roller 31 journalized in the lower part of the structure 4. From idler roller 31, the belt 15 extends rearwardly to the spring tensioned belt tightening roller 18 over idler rollers 32 on two of the uprights 5, said idler rollers 32 being disposed below the inking rollers 17.

A series of printing plates 35 of rubber, preferably, or other suitable resilient materials are cemented to the belt 15 on the outer surface thereof and spaced longitudinally along said belt so as to travel, printing face down, between the impression rollers 10, 11, and so that the printing faces engage paper or the like fed between said plates and the lower impression roller 11. Also, as will be clear, the plates 35 travel over the inking rollers 17 so that the printing faces face said inking rollers. The printing plates 35 may be provided with suitable designs embossed thereon either alike, in each instance, are alike in certain series of the plates, while being different in other series, so that the plates will print a continuous selective design, varied or uniform, as desired, and corresponding in length to the length of the endless belt 15.

A drive is provided for the lower run of the belt 15 which drives said run rearwardly from the impression rollers 10, 11 so that the printing plates 35 travel downwardly at the front of the upper impression roller 10 and rearwardly between the pair of impression rollers 10, 11, as indicated by the arrows in Figure 5. By thus driving the belt 15, the upper impression roller 10 is driven clockwise as viewed in Figure 1, and counterclockwise as viewed in Figures 3, 4 and 5. The drive comprises an electric motor 37 on the base 2 at one side of the frame 1, a belt and pulley reduction drive connection 38 between the motor 37 and one end of a transverse shaft 38' journalized in the lower portion of the platform structure 4, and a belt and pulley reduction drive connection 39 between the outer end of said shaft 38' and the driving roller 29. A suitable switch 37' controls the motor 37.

Returning now to the inking rollers 17, said rollers as shown in Figure 6, are hollow with an end filler plug 41 for filling with ink, and formed with peripheral ink discharge apertures 42. A suitable absorbent sleeve on each inking roller 17 covering the apertures 42 provides for inking the printing plates 35 as said plates pass under said rollers 17 in the lower ends of the loops 24 formed by said inking rollers 17. As will be understood, the inking is accomplished under the action of centrifugal force.

The printing plates 35 print on roll paper fed rearwardly between the belt 15 and the lower

impression roller 11 by the lower impression roller 11 which is driven oppositely relative to the upper impression roller 10 by intermeshing gears 45, 46 fast on corresponding ends of said rollers. 5 The paper is pulled by said impression roller 11 from a roll of paper 47 wound on a reel 48 secured by set screws 49 on a shaft 50 suspended transversely of the frame 1 from the top 3 thereof by hanger brackets 51 depending from said top in front of the belt 15 and in which said shaft is removably mounted. The reel 48 is adjustable along said shaft 50 to adjust the same transversely of said belt 15, as occasion may require, in placing the design on the paper. From the reel 48, the paper 47 is trained downwardly between the bearing brackets 12, in front of the impression rollers 10, 11, and under an idler roller 52 journalized transversely of the frame 1 in said brackets and from which the paper 47 travels rearwardly over and around the lower impression roller 11 so that said roller 11 frictionally drives the papers to pull the same off the roll. From the impression roller 11 the paper extends forwardly to wind up means. The wind up means comprises a rewind roller 53 in front of the impression rollers 10, 11 journalized at its ends parallel with said rollers 10, 11 in free ends of a pair of cross connected arms 54 pivoted at rear ends thereof, as at 55, for vertical swinging movement. The ends of the rewind roller 53 are journalized in notches 55 in said arms 54 for removal of said rewind roller to remove the wound up paper.

The paper 47 extends forwardly from the bottom of the lower impression roller 11 over an idler roller 56 to said rewind roller 53. Coil springs 57 suitably connected to said arms 54 and to the brackets 12 urge said arms 54 upwardly to engage the roll wound up on the rewind roller 53 with a driving roller 58 for winding up the roll of paper and which extends above and parallel with said roller 53. The driving roller 58 is journalized at one end in one bearing bracket 12 and is driven at said end by a belt and pulley connection 60 between said end and one end of the upper impression roller 10. The idler roller 56 is similarly mounted on said bracket 12 and the other bearing bracket 12 is notched at its front end, as at 61, for access to the idler roller 56 and rewind roller 53 for fastening the paper to said roller 53 in any suitable manner.

The set bolts 13 provide for adjusting the upper impression roller 10 for proper pressure engagement of the printing plates 35 with the paper 47 running between the bight of the impression rollers 10, 11.

Guide rollers 65 for the edges of the belt 15 are provided on a bracket 66 bridging the bearing brackets 12 and are adjustable horizontally relative to said edges by axle studs 67 adjustable in slots 68 in said brackets 66.

A suitable counter 70 is mounted on the brackets 66 and driven through a roller 71 riding against the belt 15 to count the number of times the belt 15 makes a complete cycle of operation.

The paper 47 may be narrower than the belt 15 and offset from the center line of said belt with the printing plates 35 similarly offset from said line, or the paper 47 may be of different widths and the printing plates 35 otherwise placed on the belt 15 according to operating requirements.

A weighted, pendant rod 75 pivoted on a transverse rod 76 on the top 3 to swing against the

roll of paper 47 acts as a friction brake to prevent over-rotation of the reel 48.

The operation of the apparatus will be readily understood. After the belt 15 has been driven through a cycle of operation, the printing plates 35 will be inked by the printing rollers 17. The paper 47 may then be pulled from the reel 48, manually, and inserted manually between the belt 15 and the lower impressions 11 and then trained from the impressions 11 up over the idler 56 to the rewind roller 53. As will be clear, further operation of the apparatus will cause the paper 47 to be pulled by the rewind roller 53 from the reel 48, the lower impression roller 11 feeding the paper beneath the plates 35 at the same rate of speed as the speed of travel of said plates so that said plates will print on the paper 47 without tearing the same.

The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

Having described the invention, what is claimed as new is:

1. Apparatus for printing a design on flexible material comprising a frame, a pair of upper and lower impression rollers mounted on said frame and geared together for drive of the lower roller by the upper roller, an endless belt within the confines of said frame trained around the upper roller to travel between said rollers in driving relation to the upper roller, horizontal series of upper and lower rollers in said frame over which said belt travels and forming vertical closely spaced loops in said belt whereby a comparatively long belt may be accommodated in a relatively shorter frame, a drive for the belt, printing plates spaced along said belt to travel between the impression rollers in facing relation to the lower impression roller, the lower series of rollers being hollow, perforated and ink containing for inking said plates under the action of centrifugal force means on said frame between said lower a roll of material for feed between said lower roller and said plates for printing on the material, said lower impression roller feeding said material from said roll, a rewind roller on said frame, and a drive from the lower impression roller frictionally engaging the material on said rewind roller to rewind the same.

2. Apparatus for printing on flexible material comprising a frame, a pair of upper and lower

impression rollers mounted on said frame and geared together for driving of the lower roller by the upper roller, an endless belt within the confines of said frame trained around the upper roller to travel between said rollers in driving relation to the upper roller, horizontal series of upper and lower rollers in said frame over which said belt travels and forming vertical closely spaced loops in said belt whereby a comparatively longer belt may be accommodated in a relatively shorter frame, a drive for said belt, printing means on said belt spaced along the same to travel between the impression rollers in facing relation to the lower impression rollers, said lower series of rollers being hollow, perforated and ink containing for inking said plates under the action of centrifugal force and means for feeding the material between the lower impression roller and said plates for printing on the material.

3. Apparatus for printing on flexible material comprising a frame, a pair of upper and lower impression rollers mounted on said frame, an endless belt within the confines of said frame trained around the upper roller to travel between said rollers in driving relation to the upper roller, horizontal series of upper and lower rollers in said frame over which said belt travels and forming closely spaced vertical loops in said belt whereby a comparatively long belt may be accommodated in a relatively shorter frame, a drive for said belt, printing plates on said belt spaced along the same and travelling between said impression rollers with said plates facing said lower impression roller, said series of lower rollers being hollow, perforated and ink containing for inking said plates under the action of centrifugal force, said lower impression roller and the plates being adapted to print on material fed between said plates and the lower impression roller.

WILLIAM B. CHANCE.
